UNITED STATES PATENT OFFICE.

WINTHROP K. HOWE, OF ROCHESTER, NEW YORK, ASSIGNOR TO GENERAL RAILWAY SIGNAL COMPANY, OF GATES, NEW YORK, A CORPORATION OF NEW YORK.

RELAY-BOND.

1,093,780.

Specification of Letters Patent.

Patented Apr. 21, 1914.

Application filed August 8, 1911. Serial No. 643,041.

To all whom it may concern:

Be it known that I, WINTHROP K. HOWE, a citizen of the United States, and resident of the city of Rochester, in the county of Monroe and State of New York, have invented a new and useful Relay-Bond, of which the following is a specification.

This invention relates to electric railway signaling, and particularly to a means for rendering the rails of the track electrically continuous for the propulsion current, by the use of the well known track relay and track transformer.

The object of the invention is to render the rails of an electrically propelled road electrically continuous at a greatly decreased cost over all known constructions.

A further object of the invention is to secure increased economy in signaling current consumption, and more reliable operation of signals.

The drawings accompanying this specification illustrate a physical embodiment of my invention, and in describing the same, reference will be had to the characters of reference thereon, like characters indicating like parts and in which:

Figure 1, is a diagrammatic illustration showing the circuits and arrangements of one physical embodiment selected to illustrate the invention. Fig. 2, is a diagrammatic representation of a modified form of the invention. Fig. 3, is a diagrammatic representation of the invention as applied to a signaling system in which all energy for the operation of the signal relay is taken from the track rails.

1, designates a direct current generator, one terminal of which is connected to the trolley or similar conducting member 2; 3, designates a car having a trolley pole or collecting shoe 4, adapted to contact with conductor 2 at all times and which serves as a means for conducting propulsion current from the conductor 2 to one terminal of the motor 5, the other terminal being connected to the axle of the car 6, which has fastened to either end the usual wheels 7, which are intended to travel upon the rails 8 and 9; the other terminal of the direct current generator is connected to the central point of a balanced iron core reactance bond 10, or may be connected to the central point of a double relay winding as more fully explained hereinafter.

A, B and C denote track circuit sections into which the rails 8 and 9 are divided by means of the well known insulating joints at the points 40 thus rendering the blocks A, B and C, electrically discontinuous for all current, so that a means must be provided for bridging the said joints so that the propulsion current may freely pass said joints but the signaling current is prevented from passing the said joints.

11, designates an alternating current generator for supplying signaling current, the two terminals being connected to the two line wires 12 and 13 extending the length of the track-way and having at each signal location or at any other desired point the primary windings 14 of transformers connected thereto; 15, designates coils wound in inductive relation to coils 14 thus constituting the secondary of a transformer, and having their two ends connected to the track rails 8 and 9 thus furnishing signaling current to the sections A, B and C. At the other end of each section are connected wires to the two track rails which convey the signaling current to a relay device. The relay device is made in the form of a poly-phase motor having 8 fixed poles 16 constituting a stator, four of which poles have coils thereon connected to a winding 17 in inductive relation with the coil 14 thus constituting the secondary of a transformer which supplies current to the coils upon the alternate poles. It will be seen by reference to the figures that the direction of the turns about one pole is opposite to the direction of the turns about the next succeeding alternate pole, so that the magnetic polarity of said poles is opposite. The four poles to which the current is fed from the transformer secondary 17 constitute a means by which the greater amount of energy needed to cause the relay device to act, is supplied, and to those skilled in the art, is easily recognized as constituting what is ordinarily known as the "local phase of the relay."

The wire 18 from rail 9 is connected with a coil wound upon each alternate pole of the relay device, the turns upon each pole being made in a direction opposite to those on the preceding pole; the wire 19 from track rail 8 likewise passes about each alternate pole of the relay device and in the same way the turns upon each pole are opposite in direction to the turns upon the pre-

ceding pole and the turns upon any one pole connected to wire 19 are opposite in direction to the turns upon the same pole connected to wire 18. The wires 18 and 19 after passing about the poles are joined together at the point 20 and a wire 21 leads from the connection 20 to the central point of the windings constituting the secondary 15 of the transformer. The alternating signaling current generated in secondary 15 connected to the two rails of track section B may be assumed to flow in the direction of the arrow *a* shown just above the transformer winding and to pass by the wire 22 to rail 9 along rail 9 to wire 18, about the first pole on which it is wound in a clockwise direction, about the second pole in a counterclockwise direction, upon the third pole in a clockwise direction and upon the fourth pole in a counterclockwise direction then passing by means of the connection 20 about the last mentioned pole in a counterclockwise direction, then passing to the third mentioned pole and passing about it in a clockwise direction, then passing around the second mentioned pole in a counterclockwise direction and then about the first mentioned pole in a clockwise direction and thence by wire 19 to the other rail 8, along the rail 8 to the wire 23 and to the other side of the transformer secondary 15, thus making a complete circuit. It will be noticed that the current passes around each alternate pole and then in returning passes around the same alternate poles, and it should be noted furthermore that the magnetic flux generated by the current the first time it passes about the alternate poles is in the same direction as the magnetic flux generated by the current when it again passes about the alternate poles, for, although the coils through which it passes the first time are wound reversely to the coils through which it passes the second time, nevertheless, as the direction of current is reversed the magnetic flux generated is in the same direction. If a car were traveling upon section C as shown, the propulsion current would flow from the direct current generator 1 by means of conductor 2, trolley 4, motor 5, axle 6 and wheels 7 to each track rail 8 and 9 and along each track rail to the wires 18 and 19 flowing in the same direction as shown by the arrows *b* in each wire and would flow through the coils wound about the alternate poles to the junction point 20 where the current flowing in both wires 18 and 19 would unite and flow by wire 21 to the central point of transformer secondary 15, again dividing and flowing by both halves of the secondary windings to wires 22 and 23 and thus to the rails 8 and 9 and along rails 8 and 9 to wires 18 and 19 in section B through the relay device as in section C to the central point of the transformer in sec-

tion A and by the two wires 22 and 23 to the two rails 8 and 9 of section A along the rails 8 and 9 to the reactance bond 10 and by the wire 25 to the other terminal of the direct current generator thus making a complete 70 circuit.

It is to be noticed, that although the propulsion current flowed through the coils wound upon the poles of the relay device, no effective magnetic energization of said poles was effected, because the current in wire 18 was in the same direction as the current in wire 19 and wire 18 being connected to a coil on a pole which is wound reversely to the coil to which wire 19 is connected on the same 75 pole, neutralization or equalization of the magnetic effect caused by the two coils is effected and the same phenomenon occurs at each pole, therefore, there is no magnetic saturation of the stator of the polyphase 80 motor.

It is to be observed that the arrangement illustrated and adopted is much more efficient than the ordinary and well known form of T or balanced bond construction, for in 90 the arrangement shown, the energization of the relay device from the current furnished to the track circuit, does not depend upon a drop of potential through a T or balanced bond, but the whole current from the source, 95 which in this case is the transformer secondary 15, flows twice about each alternate pole of the relay device, so that a great economy in signaling current is effected or, with the same consumption of signaling current the sections may be made longer. As 100 four of the poles of the motor are constantly energized from the source of signaling current and as the other four poles would be energized if no connection were present between rails 8 and 9, a turning torque would, under such conditions, be imparted to rotor 26 in the direction of the arrow *c*, thus causing the arm 27 to bridge the wires 28 and 29 thus completing a circuit through the signal 110 30 and the transformer secondary 31, so that the signal would thereby be moved to the clear position. If a train came upon one of the sections A, B or C, the signaling current would be shunted from the relay, therefore, the track phase of the relay would be deenergized, consequently, the armature 26 would move by gravity to its lower position, thus destroying the bridge across wires 28 and 29 and so interrupt the circuit from 120 transformer secondary 31 to the signal and consequently allow the signal to go to danger by the withdrawal of the energizing current.

In Fig. 2, the continuity of the rails for 125 propulsion current is effected between sections A and B by employing the well known balanced bond 10 in section B, the ends of which are connected to the two rails 8 and 9 of the section B and the central point of which is connected to the central point of the 130

transformer secondary 15 used for supplying signaling current to the section A; the relay device in section B, in this case, consisting of the ordinary and well known polyphase 5 motor relay the armature of which is designated by 26, the locally fed phase being designated by 32 and the track fed phase by 33. A path from section C to section B for the propulsion current is effected by placing 10 the well known reactance bond 10 in section B, connecting in the well known manner, the central point of the reactance bond 10 by the wire 21 to the junction point 20 of the relay windings in section C. Fig. 2 is 15 merely designed to show that applicant's invention may be embodied in a form which does not realize to the full, all of the advantages flowing from it.

In Fig. 3, applicant's invention is shown 20 in connection with a polyphase relay which derives all of its energy from connection to the track rails. In this figure the source of propulsion current 34 is shown as an alternating current generator. Signaling current 25 from the generator 11 through the primary winding 14 of the transformer is induced in secondary winding 15 which is connected to the two track rails 8 and 9 the current being considered to flow in the direction 30 of the arrow *a* in the secondary of the transformer, and to flow through the wire 22 to rail 9, along rail 9 to wire 35 thence around four alternate poles of the relay device to the junction point 20 then back again around 35 the same four alternate poles to the wire 36, which connects with rail 8 and then along rail 8 to wire 23 and thus to the other side of the secondary 15. The current in the above traced path energizes one winding of the relay. The other phase of the relay is derived 40 through the following circuit starting from wire 35; wire 37, ohmic resistance *g*, wire 38, through the coils upon four alternate poles of the relay device, wire 39, ohmic resistance *f*, 45 and wire 36 to rail 8. On account of the ohmic resistances *g* and *f*, the proper phase displacement in the two windings in the relay device is effected and consequently rotor 26 holds the bridge 27 in contact with wires 28 50 and 29. The object of the connections and devices consisting of reactances *d* and *e* and ohmic resistances *f* and *g* is to protect the relay from the effects of alternating propulsion current flowing therethrough. If either 55 of the rails 8 or 9 should break and a car propelled by current from the alternating generator 34 were traveling on the rails, the other side of the break from where the relay is connected, there would be a difference of 60 potential between the two rails at the relay which would cause alternating propulsion current at the usual frequency, to-wit: 25 cycles to flow through wires 35 and 36 which, if the relay were connected as in ordinary 65 practice, with nothing but the ordinary

phase splitting device between the two phases of the relay, would be liable to cause a dangerous operation of the relay, that is, the 25 cycle propulsion current might cause the relay to close. By using the combination 70 of reactances and resistances as shown, and by properly proportioning the same and taking advantage of the fact that a reactance has very much less reactive effect upon a 25 cycle current than it does upon a 60 cycle 75 current, the relay may be made immune to deleterious effects caused by the flow of propulsion current therethrough. The operation and effect of the phase changing device composed of the resistances *f* and *g* and *d* 80 and *e*, is fully shown, described and claimed in the application of James Burke, Serial No. 635,885, filed June 28th, 1911. Just as in the embodiments shown by Fig. 1, the junction 20 may be connected by means of the wire 21, to the center point of the windings 85 of transformer secondary 15, thus forming a connection for the propulsion current from one section to the next.

Having explained the principle of my invention and illustrated and described one physical embodiment thereof, what I claim as new and desire to secure by Letters Patent, is:

1. In a signaling system for electric rail- 95 ways, a source of propulsion current, a trackway composed of two lines of rails, insulating means interposed in each line of rails at approximately opposite points at intervals forming sections, a relay having a field winding, the two ends of the winding being connected to the two rails at one end of a section, means to energize the relay, means connecting the middle point of the winding to the two rails at the end of the next section 100 adjacent the relay, said means affording a path for propulsion current, and a signal device controlled by the relay.

2. In a signaling system for electric rail- 110 ways: a source of propulsion current; a trackway composed of two lines of rails; insulating means interposed in each line of rails at approximately opposite points at intervals forming sections; a relay having a field piece of magnetic material; a plurality 115 of coils wound thereon, said coils being disposed in pairs, and the corresponding coils of the several pairs being joined in a series; a conductor connecting the end coil of one series with one track rail and a conductor 120 connecting the end coil of the other series to the other track rail, that pair of coils which form the other end coils of the two sections being joined together forming a junction; a conductor connecting the junction to the two 125 rails of an adjacent section, said conductor affording a path for propulsion current; means to energize the relay; and a signal device controlled by the relay.

3. In a signaling system for electric rail- 130

ways: a source of propulsion current having two terminals; a feeder extending from one terminal of the source; a trackway composed of two lines of rails; insulating means interposed in each line of rails at approximately opposite points at intervals forming sections; a relay having a field piece of magnetic material; a plurality of coils wound thereon, said coils being disposed in pairs, and the corresponding coils of the several pairs being joined in a series; a conductor connecting the end coil of one series with one track rail and a conductor connecting the end coil of the other series to the other track

15 rail, that pair of coils which form the other end coils of the two sections being joined together forming a junction; means connecting said junction with the said other terminal of the source of current; means to energize the relay; a signal device controlled by the relay; and a car having an electrical propelled means having two terminals, one of the terminals in contact with the feeder, the other in contact with the trackway.
